UNITED STATES PATENT OFFICE

2,048,641

BUILDING CONSTRUCTION

Frederick M. Venzie, Philadelphia, Pa., assignor
to National Gypsum Company, Buffalo, N. Y.,
a corporation of Delaware

Application April 1, 1933, Serial No. 663,916

14 Claims. (Cl. 72—118)

My invention relates to building construction and more particularly to a novel means for attaching surfacing units such as panels to a supporting framework.

5 The present invention contemplates the use of construction units such as panels of plaster board and a conventional supporting framework such as is frequently made up of either wooden risers or such metal units as plasterer's channels and the like, and includes the provision of novel clips for connecting the surface units to the supporting members. Such clips include a resilient member adapted to form a portion of the linkage between the surfacing units and the support whereby the 15 surfacing units may have a certain amount of "give" with respect to their supports.

An object of my invention is to provide a novel resilient clip which, when the pressure is applied to the surfacing unit supported by the clip, will allow the unit to move with the pressure. Such a result is particularly desirable in those building constructions where an effort is being made to reduce noises and to impart to the walls a sound absorbing characteristic.

20 Another and more specific object of my invention is to provide a clip having resilient characteristics which may be readily applied to a support and to which surfacing units may be connected.

25 Another object of my invention is to provide a novel resilient clip in which the spring functions as a portion of the means for holding a panel in position.

30 Yet another object of my invention is to provide a clip which may equally well be applied to either a wood or metallic support.

35 Other and more specific objects and advantages of my invention will be apparent from the following specification, claims, and from the drawings, 40 in which:

Fig. 1 is a side elevation of one form of clip embodying my invention as attached to a wooden support;

45 Fig. 2 is a front elevation of the embodiment illustrated in Fig. 1;

Fig. 3 is a front elevation of the spring embodied in the invention illustrated in Figs. 1 and 2;

50 Fig. 4 is a detail perspective view of the panel holding portion of the clip illustrated in Figs. 1 and 2;

Fig. 5 is a side elevation of another embodiment of my invention;

55 Fig. 6 is a front elevation of the embodiment of my invention illustrated in Fig. 5;

Fig. 7 is a plan view of the embodiment of my invention illustrated in Figs. 5 and 6;

Fig. 8 is a front elevation of a spring which may be used in connection with the embodiment of my invention shown in Figs. 5 to 7 and 9 to 11;

Fig. 9 is a side elevation of another embodiment of my invention;

Fig. 10 is a plan view of the embodiment of my invention shown in Fig. 9;

Fig. 11 is a front elevation of the embodiment 10 of my invention shown in Figs. 9 and 10;

Fig. 12 is a side elevation of the embodiment of my invention shown in Fig. 1 as applied to a metal supporting member;

Fig. 13 is a front elevation of the embodiment 15 of my invention shown in Fig. 12;

Fig. 14 is a front elevation of another embodiment of my invention;

Fig. 15 is a plan view of the embodiment of my invention shown in Fig. 14; and

Fig. 16 is a side elevation of the embodiment of my invention illustrated in Figs. 14 and 15.

Referring now particularly to the embodiment of my invention shown in Figs. 1 to 4 and 12 and 13, a clip C comprises two essential elements, 25 a curved spring 20 and a panel holding member 21 affixed to a flange 22 lying in a plane at a right angle to the spring by a rivet 23. The upper end of the spring 20 is flattened and lies in a plane parallel to the fingers of the panel holding member 21 and is perforated as at 24 for the reception of nails 25 by which it may be attached to a wooden support W. The flange 22 is positioned adjacent a flat portion 20a of the spring 20 and is bent at its outer end 26 at a right angle into 35 substantially parallel relationship with the flat portion 20a of the spring 20 to assist in maintaining the member 21 on the flange 22. If the clip is applied to the walls of a building, this may be sufficient to hold the member in place and the 40 rivet 23 may be eliminated.

The member 21 comprises a body portion 27 from the opposite ends of which extend at right angles thereto fingers 28 having outwardly flaring ends and from the middle portion of which 45 extends a finger 29 at right angles to the body portion 27 and in a direction opposite to the fingers 28. The finger 29 cooperates with the face of the flat portion 20a of the spring 20 to hold in position a panel P and the fingers 28 engage the 50 upper end of a panel or panels beneath the plate. It will be obvious that with the construction above described the clip may be placed in position above the lower panel, the spring nailed to the wooden support and the upper panel then placed in posi- 55

- tion and such a process may be followed as course after course is built up. The clip illustrated in these figures may equally well be applied to a metal support **M** as illustrated in Figs. 12 and 13.
- 5 In this instance the support is arranged at right angles to the longitudinal axis of the clip and the upper end of the spring **20** may bend over and be clinched around the support as illustrated.
- In the embodiment of my invention shown in
- 10 Figs. 5 to 8 inclusive the clip may more properly be spoken of as supporting the spring than the reverse. As herein illustrated the spring is adapted for connection only to a metallic support and it may be identical with that shown in Fig. 1 et seq. above described, but the flattened end portion provided with holes is eliminated. In this embodiment the spring **30** carries a centrally located flange **31** upon which is positioned a panel holding member **32** held in position by a rivet **33**.
- 15 The member **32** comprises a plate **34** having at its opposite ends opposed pairs of downwardly extending fingers **35** adapted to engage the upper end of a panel **P** and a centrally located upwardly extending finger **36** adapted to co-operate with a centrally located flat face **30a** of the spring **30** to hold in position a panel resting upon the plate **34**. The plate **34** carries in its own plane two rearwardly extending L-shaped flanges **37** the end of one of which extends upwardly and the end of the other of which extends downwardly for engagement about a channel member **C**. In this embodiment of my invention the spring is always under tension as upon this tension depends the maintenance of the clip in its position with regard to the channel.

In the embodiment of my invention shown in Figs. 9 to 11 inclusive, the spring **40** which may be identical with that shown in Fig. 5 et seq. carries, on a flange **41**, the panel supporting member **42** comprising a plate **43** having at opposite ends, opposed downwardly extending pairs of fingers **44** and having an oppositely and separately disposed finger **45** extending upwardly opposite to a flat portion **40a** of the spring **40**. From the plate **43** and in the same plane extends an arm **46** carrying at its outer end at right angles thereto and at least partially in the same plane, a finger **47** adapted to be bent around the rear face of a channel member **C**. In this embodiment the finger **47** co-operates with the spring **40** to maintain the clip in predetermined position with respect to its support.

In the embodiment of my invention, adapted for connection to a wood support, shown in Figs. 14 to 16 inclusive, spring **50** may be identical with that shown in Fig. 3 except that the flange has no upward bend. The panel holding member comprises a plate **51** at opposite ends of which extend pairs of upwardly extending fingers **52** centrally of which extend downwardly pairs of opposed fingers **53**. Centrally of the clip are disposed two upwardly extending fingers **54** and **55** the finger **55** being to the rear of the clip and having at its ends flanges **56** adapted to be bent as at **57** about the spring **50** and hold the member in predetermined position with respect to the spring.

Various modifications may be made in the foregoing embodiments of my invention without departing from the spirit and scope thereof as set forth in the following claims.

What is claimed is:

1. A clip comprising panel engaging means and means for resiliently connecting said first named

means to a support, said last named means forming a part of said first named means.

2. A clip comprising a spring having a flat surface, a flange lying in a plane normal to said surface, a member having a plurality of panel engaging fingers, and means for connecting said member to said flange in a position whereby one of said fingers co-operates with the flat portion of said spring to engage a panel.

3. A clip comprising a spring having a flat surface, a flange lying in a plane normal to said surface, a member having a panel engaging finger, and means for connecting said member to said flange in a position whereby said finger co-operates with the flat portion of said spring to engage a panel.

4. A clip comprising a spring having a flat surface, a flange, a member having a panel engaging finger, and means for connecting said member to said flange in a position whereby one of said fingers co-operates with the flat portion of said spring to engage a panel.

5. A clip comprising a spring, a flange, a member having a panel engaging finger, and means for connecting said member to said flange in a position whereby one of said fingers co-operates with said spring to engage a panel.

6. A clip comprising a finger, a spring co-operating with said finger to engage a panel positioned between said finger and said spring, and means for connecting said clip to a support.

7. A clip comprising a unitary structure including means embracing a metallic support and means embracing a wall panel, and means fixed to said unitary structure resiliently engaging said support and holding said support embracing means in contact therewith.

8. In a wall construction in combination with a penetrable support; a clip comprising a perforated spring, a flange on said spring, a member having a panel engaging finger, means for connecting said member to said flange in a position whereby one of said fingers co-operates with said spring to engage a panel; and means passing through the perforation in said spring and penetrating said support for connecting said clip to said support.

9. In a wall construction in combination with a penetrable support; a clip comprising a perforated spring, a flange on said spring lying in a plane at a right angle to the plane of said spring, a member having a panel engaging finger, means including a finger on said flange parallel to said spring for connecting said member to said spring; and means passing through the perforation in said spring and penetrating said support for connecting said spring to said support.

10. In a wall construction in combination with a support; a clip comprising a spring, a flange on said spring lying in a plane at a right angle to the plane of said spring, a member having a panel engaging finger, means including a finger on said flange parallel to said spring for connecting said member to said spring, and means for connecting said spring to said support.

11. In a wall construction, in combination with a support; a spring, a flange on said spring; a member having a panel engaging finger, means for connecting said member to said flange in a position whereby one of said fingers co-operates with said spring to engage a panel, and means on said member for maintaining said spring in contact with said support.

12. In a wall construction, in combination with a support; a spring, a flange on said spring; a

member having a panel engaging finger seated on said flange; and means on said member connecting said member to said flange in a position whereby one of said fingers co-operates with said spring to engage a panel.

5. 13. In a wall construction, in combination with a support; a spring engaging said support; a member connected to said spring and a rigid finger on said member co-operating directly with

said spring to engage a panel between said spring and said finger.

14. A clip comprising a plurality of fingers, a spring co-operating with one of said fingers to engage a panel positioned between said fingers and said spring, and means for connecting said clip to a metallic support. 5

FREDERICK M. VENZIE.
